UNITED STATES PATENT OFFICE

163,104

ELECTRIC COPYING MACHINE

Henry Dreyfuss, Pasadena, Calif., assignor to
Timefax Corporation, New York, N. Y., a corpora-
tion of New York

Application January 19, 1951, Serial No. 13,884

Term of patent 14 years

(Cl. D64—11)

To all whom it may concern:

Be it known that I, Henry Dreyfuss, a citizen of the United States of America, residing at 969 San Pasqual Street, Pasadena 5, California, have invented a new, original, and ornamental Design for Electric Copying Machine, of which the following is a specification, reference being had to the accompanying drawing, forming part thereof.

Referring to the drawing:

Fig. 1 is a perspective front view of an electric copying machine, showing my new design.

Fig. 2 is a front face view of the machine of Fig. 1.

Fig. 3 is a right-hand side elevational view of the machine of Fig. 1.

I claim:

The ornamental design for an electric copy-
ing machine, as shown.

HENRY DREYFUSS.
